Primary Examiner — Dominic Simone*(74) Attorney, Agent, or Firm* — Morgan, Lewis & Bockius LLPCLAIM

The ornamental design for a single-sole shoe with blue stripe and blue sole, as shown and described.

DESCRIPTION

The file of this patent contains at least one drawing executed in color. Copies of this patent with color drawing(s) will be provided by the Office upon request and payment of the necessary fee.

- FIG. 1 is a perspective view of an embodiment of our new design of a single-sole shoe with blue stripe and blue sole; FIG. 2 is a first side view thereof; FIG. 3 is a second side thereof; FIG. 4 is a top view thereof; FIG. 5 is a bottom view thereof; FIG. 6 is a front view thereof; FIG. 7 is a back view thereof; FIG. 8 is a perspective view of another embodiment of our new design of a single-sole shoe with blue stripe and blue sole, where the blue portions are indicated using the USPTO convention of horizontal lines for blue; FIG. 9 is a first side view thereof; FIG. 10 is a second side view thereof; FIG. 11 is a top view thereof; FIG. 12 is a bottom view thereof; FIG. 13 is a front view thereof; FIG. 14 is a back view thereof; FIG. 15 is a perspective view of yet another embodiment of our new design of a single-sole shoe with blue stripe and blue sole, where the blue portions are indicated using a cross-hatched pattern to indicate the blue color Pantone 7466C;

FIG. 16 is a first side view thereof;
FIG. 17 is a second side view thereof;
FIG. 18 is a top view thereof;
FIG. 19 is a bottom view thereof;
FIG. 20 is a front view thereof; and,
FIG. 21 is a back view thereof.

The broken lines illustrating the half moon patch and the channel on the blue sole in the above described Figures are for illustrative purposes only and form no part of the claimed design.
